UNITED STATES PATENT OFFICE.

JAMES S. BRENNAN, OF NORTH ATTLEBOROUGH, MASSACHUSETTS, AS-SIGNOR TO MCRAE & KEELER, OF ATTLEBOROUGH, MASSACHUSETTS.

DESIGN FOR A BADGE.

SPECIFICATION forming part of Design No. 29,484, dated October 18, 1898.

Application filed September 22, 1898. Serial No. 691,645. Term of patent 3½ years.

To all whom it may concern:

Be it known that I, JAMES S. BRENNAN, of North Attleborough, in the county of Bristol and State of Massachusetts, have invented and produced a new and original Design for a Badge or Similar Article, of which the following is a specification, reference being had to the accompanying drawings, forming part thereof.

Figure 1 is a front view, and Fig. 2 is a vertical sectional view, showing my design.

The leading features of my design consist in the raised surface representing the bust of a human being and a surface having the outline and configuration of the head of a human being connected with the bust by a cylindrical connection resembling a long neck.

In the drawings, *a* indicates the main body

of the badge, having the outline and configuration of the bust of a man; *b*, a cylindrical extension, and *c* a plate having the outline and configuration of a man's head.

The whole design presents to the eye the appearance of a man having an excessively long and apparently flexible neck.

Having thus described my invention, I claim as new and desire to secure by Letters Patent—

The design for a badge or similar article substantially as herein shown and described.

In witness whereof I have hereunto set my hand.

JAMES S. BRENNAN.

Witnesses:

A. A. MCRAE,
J. F. STREETER.
